RICHARD C. LEAKE, OF ROCHESTER, NEW YORK, ASSIGNOR TO GENERAL RAILWAY SIGNAL COMPANY, OF GATES, NEW YORK, A CORPORATION OF NEW YORK.

RAILWAY SIGNALING SYSTEM.

1,330,125.

Specification of Letters Patent. Patented Feb. 10, 1920.

Application filed June 5, 1916. Serial No. 101,748.

To all whom it may concern:

Be it known that I, RICHARD C. LEAKE, a citizen of the United States, and a resident of the city of Rochester, in the county of Monroe and State of New York, have invented a new and useful Improvement in Railway Signaling Systems, of which the following is a specification.

This invention relates to devices adapted for use in controlling electric circuits and more particularly for use with electric circuits for railway signaling.

One of the principal objects of this invention is to so devise and construct a means that electric circuits which are controlled from a distant point may be intermittently opened and closed for any length of time.

Another object of this invention is to provide a signaling system comprising a means, selectively controlled from a distant point and used in conjunction with the ordinary block signaling where light signals are used, for giving an additional indication which is distinctive in character.

Another object of this invention is to provide a signaling system comprising a means, selectively controlled from a distant point and used in conjunction with the ordinary block signaling where light signals are used, for causing the lights of said light signals to be intermittently flashed for any length of time.

Another object of the invention is to so devise and construct a system for railway signaling to obtain the above mentioned objects, that it may be practically and inexpensively put together to provide a means controlled from a distant point for causing a light signal to give an additional indication, distinctive in character, without changing the construction or automatic operation of said light signal.

Other objects and advantages will appear as the description progresses and the novel features of the invention will be particularly pointed out in the appended claims.

The embodiment of the invention shown consists generally of a signaling system for railways wherein are used light signals of the ordinary type well-known to those skilled in the art of railway signaling, said light signals having different indications which are automatically controlled from insulated sections of a railway track and an additional indication which is selectively

controlled from a central station and does not alter or interfere with the signal or the independently controlled indications of the light signal, and in addition to the above named conditions a check may be obtained to satisfy the despatcher or person at the central station of the operating or other condition of the said signal.

Another advantage of the embodied system is to make it possible for the despatcher at a central station to keep in touch with the operators of trains along his particular division. For example it may be the despatcher's wish to have said operator either stop and call the despatcher's office by a telephone conveniently placed along the trackway or he may wish him to take the next siding and allow another train to pass or to perform any other duties which may be set forth in the rules of the road for such conditions. This is made possible, in a system where light signals are used, by the despatcher being able to control signals which are usually located near sidings for causing such signals to give an indication that will be distinctive in character from the indication which has been given automatically by the signal, such a distinctive indication being given by causing the signal lamp lighted to be flashed continuously.

In describing the invention in detail reference is had to the accompanying drawing wherein is pictured in a single view a diagrammatic illustration of the circuits and apparatus selected for the purpose of exhibiting a particular physical embodiment of the idea of means underlying my invention.

The system of signaling herein embodied involves the use of an answer-back mechanism. This answer-back mechanism may be of any type suitable to perform the functions peculiar to the system herein shown and is preferably of the type fully shown and described in my prior application filed March 25, 1915, Serial Number 16,863. It is therefore considered that a simplified diagram of the answer-back mechanism as shown in the accompanying drawing will be sufficient for a clear understanding of the present invention. This answer-back mechanism is represented generally by letter A in the accompanying drawing and consists of an answer-wheel 1

revolvably mounted on rollers 2 adapted to bear on the inner periphery of said answer-wheel 1, said rollers 2 being revolvably carried on pins 3 fixed in a front frame plate (not shown). The outer periphery of said answer-wheel 1 has equally spaced teeth 4 of different lengths formed therein, the longer teeth being arranged in equally spaced code groups. Bearing on the inner periphery of said answer-wheel 1 and 50

10 spring pressed outwardly from the center of said answer-wheel 1, are contact arms 5 and 6 which are pivotally fastened to binding posts 7 and 8 respectively. Carried on 15 the lower end of each contact carrying arm 5 and 6, are rollers 9 of insulating material adapted to ride on the said inner periphery of said answer-wheel 1 and to coact with a notch 10 formed in said inner periphery. 20 On either side of said answer-wheel 1 is shown an electro-magnet, comprising coils 11 and 12 respectively together with their pole pieces 13 and 14 respectively. Coacting 25 with said electro-magnets is an oscillatable armature 15 having fixed thereto and oscillatable therewith an upstanding arm 16, at the upper end of which is fixed a bearing pin 17. Loosely carried on said bearing pin 17 are laterally extending 30 pawls 18 and 19 having at their outer ends projections adapted to engage the teeth 4 on the answer-wheel 1. Fixed in said front frame plate (not shown) and insulated therefrom is a contact post 20 with which 35 contact springs 21 and 22, on contact carrying arms 5 and 6 respectively, are adapted to coact as will be hereinafter more fully explained. Oscillatably supported on a shaft (not shown) is a control armature 23 associated with said pole pieces 13 and 14 40 and having a downwardly projecting arm 23¹. At the lower end of said arm 23¹, on member 23 are fixed laterally projecting blocks 23², 23³ and 23⁴ of insulating material 45 which are adapted to strike the downwardly extending contact springs 24, 25 and 26 as the member 23 is rocked in one direction or the other. An arm 27, pivotally supported at one end on a binding post 28, 50 fixed to said front frame plate (not shown) and insulated therefrom, is biased to the position shown and carries at its other end a T shaped member 29. This member 29 carries at its lower end a roller 30 adapted 55 to coact with the longer teeth 4 on said answer-wheel 1. At the upper end of said T shaped member 29 is an L shaped conductive head plate 29¹ carrying two contacts 31 and 32 which respectively oppose but 60 are normally separated from contacts 33 and 34 which are held in contact springs 35 and 36 respectively. The said contact springs 35 and 36 are held in the respective binding posts 37 and 38 which are fixed in 65 the said front frame plate (not shown) and

insulated therefrom. The L shaped head plate 29¹ also carries a non-conductive presser part, preferably a roller 39 which opposes the inner end of a contact spring 40 held in a binding post 41 fixed to and insulated from front frame plate (not shown). This contact spring 40 carries a contact 42 opposing but normally separated from a contact 43 on contact spring 44 held in a binding post 45 fixed to and insulated from the front frame plate (not shown). The raising of the member 29 by coacting with the longer teeth 4 on the answer-wheel 1 will bring all three pairs of contacts, above mentioned, together, for closing certain answer-back circuits, hereinafter mentioned. For a further and more detailed description of the operation and construction of the answer-back mechanism reference may be had to the above mentioned application 85 of Richard C. Leake Serial Number 16,863. 80

This system also involves the use of a selector of any well known type capable of responding to impulses, imparted thereto from a pair of line wires connected with a sending station or device located at a distant point, for causing a plurality of different circuits to be selectively closed. The selector preferably used and shown at B is of the type shown and described in the Patent #1,118,120 granted to Maurice F. Geer and Richard C. Leake, March 24, 1914, and consists of a pair of magnet coils 47 and 48 together with their respective cores 49 and 50 suitably supported in a pole piece 100 (not shown) which is fixed to a front plate 51. Associated with said magnet coils 47 and 48 and their respective cores 49 and 50 is an oscillatable armature 52 suitably held against and capable of being oscillated about its knife edge bearing 53. Attached to the said armature 52 and adapted to oscillate therewith is an upstanding arm 54 carrying at its upper end a fixed bearing pin 55 on which are loosely supported laterally extending pawls 56 and 57 which are adapted to engage with the teeth on sectors 58 and 59 which are loosely supported on a shaft 60 fixed in the front plate 51 and to rotate said sectors independently and separately about said shaft, the sectors being held in their moved position by dogs 61 and 62 respectively. Associated with said selector are three groups of normally open contact fingers fixed to a block 63 of insulating 110 material and for convenience are herein designated by the terms HI, ST, and CL respectively and will be hereinafter so called. Each of said groups of contact fingers HI, ST and CL comprising opposed sets of 120 normally open contact fingers adapted to be closed when the arms 64 and 65 fixed to sectors 58 and 59 respectively are properly actuated as fully explained in the Patent #1,118,120 hereinbefore referred to. 130

The answer-back mechanism A and the selector B hereinabove described are each connected across the line wires J and are protected against high voltages due to lightning by a lightning arrester 195 of any well known type which is connected across the line wires J and is also connected to ground 197 by wire 196.

The signaling system as herein set forth includes a central station or despatcher's office located at a point distant from the devices to be controlled and wherein are located apparatus for sending impulses over the said line wires for operating the selector at a distant point which in turn controls other devices similarly located from the central station, and for receiving indications sent back over the line to the central stations by the devices operated. This apparatus is represented generally in the accompanying drawings by the letter C. The device for sending the impulses over the line wires may be any of the well known types of selective calling keys and preferably one of the type shown and described in the Patent No. 1,105,766 granted to Maurice F. Geer and Richard C. Leake August 4, 1914, but for the sake of simplicity is shown in the accompanying drawing as a simple telegrapher's key 66 of the make and break type connected across the said telephone line wires J. Associated with said key 66 and interposed in the circuit of said key 66 is a pole changing device of the ordinary type comprising two pivoted armatures 67 and 68 and three contact buttons 69, 70 and 71. The contact buttons 69 and 71 being connected to one side of battery 72, also interposed in the circuit for key 66, and contact 70 being connected to the other side of the battery 72 so that when the pole changer is in one position, impulses of one polarity may be sent over the line wires J and when the switch is moved to its other position, impulses of an opposite polarity may be sent over the line wires J. Impedance coils 73 and 74 are also interposed in the circuit for the key 66 to subdue or minimize the noises caused by the making and breaking of the circuit at the key 66 thereby avoiding disagreeable sounds in the telephone receiver 75 which is also included in the equipment shown at the central station and is also connected in bridge across the telephone line wires J.

Conventionally shown on the accompanying drawing and designated by the letter D is a polarized relay herein termed a stop relay of the well known type comprising a pair of magnet coils 76 and 77 together with their cores 78 and 79 respectively. An armature 80 pivotally supported at its middle is arranged to be attracted by either of the cores 78 or 79; and when so attracted is held in this position, preferably by including a permanent magnet in the magnetic circuits.

This armature 80 is divided by insulation 80¹ and carries on opposite sides upstanding contact arms 81 and 82 insulated from each other and adapted to make contact with contact points 83 and 84 respectively when said armature is attracted by either one or the other of said cores 78 or 79. The coils 76 and 77 on the polarized relay D are selectively controlled by the selector B and in turn automatically control the direction of rotation of the answer-wheel 1 as will be hereinafter more fully explained.

The insulated section of trackway shown on the drawing and represented by the letter E comprises the rails 85 and 86 and their insulations 87. Connected across one end of the rails 85 and 86 by the wires 88 and 89 is the secondary 90 of the transformer K and connected across the other end of said rails 85 and 86 by wires 91 and 92 is the coil 85 of the track relay F an armature 93 of which being adapted to at times coact with contacts 94 and 95. This track relay F is conventionally shown on the drawing and may be any of the well known types. For convenience it has been herein illustrated as an alternating current device.

The signal illustrated conventionally on the drawing and designated by the letter G is shown as a light signal of the well known type. This signal is controlled through the track relay F and obtains its electrical energy from a transformer L also connected across the transmission line I. However, it is not contemplated to limit this invention to a particular type of signal for it may obviously be used with various other types of signals or devices not signals, and its energy may be derived from various sources.

Also conventionally illustrated in the drawing and represented by the letter H is a stick relay of the kind before mentioned together with its armatures 96, 97 and 98 and their coöperating contacts 99, 100, 101 and 102.

The apparatus shown grouped together on the drawing and represented by the letters A—B—D—F—G and H constitutes the equipment of only one way station or signal along a division of a railway and there may be any number of groups similarly arranged at any number of other way stations or signals, each being selectively controlled from the same central station herein represented by the letter C. The selector B for each of said way stations has its arms 64 and 65 relatively adjusted to respond to different sets of impulse combinations to cause them to be brought in proper alignment to close any pair of contacts of said contact groups herein represented by III, ST and CL, said groups being the same on all selectors.

The operation of the selector B is fully described in the Patent No. 1,118,120 above mentioned and it is believed that the follow-

ing brief description of said operation will be sufficient at this time.

Referring to the accompanying drawing, an illustrated example may be had. Should the despatcher wish to operate the HI contacts on the selector B, the combination for this pair of contacts being 3-5, he would cause armature of the key 66 to be pressed against the contact point 114 and the following circuit will be established: from one side of the battery 72, wires 122 and 123, contact button 71 and arm 67 of the pole changer in its lefthand position, wire 116, impedance 74, wires 117 and 118, wire 132 of the telephone line wires J, wires 131, 130, 129, the righthand coil 48 of the selector B, wire 128, the lefthand coil 47 of the selector B, wires 127, 126 and 125, wire 124 of the telephone line wires J, wires 119 and 120, impedance 73, wire 121, telegrapher's key 66, contact point 114, wire 115, arm 68 of the pole changer in its lefthand position, contact button 70 and wire 133 back to the other side of the battery 72. The circuit above traced will cause current of a certain polarity to energize the coils 48 and 47 of the selector B and the sector 59 of the selector B to be picked up one tooth and the arm 65 to be carried with it. To obtain the combination desired, namely 3-5 the despatcher would cause the key 66 to be pressed three successive times thereby setting up the above traced circuit for each operation of the key and causing three impulses of the same polarity to be sent over the line wires J and the selector arm 65 to be moved three steps in the counterclockwise direction bringing the said selector arm 65 in alinement with the HI contact fingers. Next the despatcher will move the pole changer from its left hand position as shown in the drawing to a right hand position so that the arms 67 and 68 will move out of contact with contact buttons 71 and 70 respectively and into contact with contact buttons 70 and 69 respectively. From the foregoing description it will be obviously apparent that when the key 66 is caused to be pressed five times, with the pole changer in the condition described, that current flowing through the coils of the selector B in an opposite direction will actuate the armature 52 in an opposite direction until the selector arm 64 is in alinement with the selector arm 65 and the HI contacts. When the arms 64 and 65 are in the condition just described an additional impulse will be sent over the line wires J from key 66 with the pole changer in the first mentioned or lefthand position which will close the HI contacts in a manner fully explained in the above mentioned patent #1,118,120 granted to Maurice F. Geer and Richard C. Leake. Having briefly described the operation of the selector for one combination it should be apparent that, by

sending out different numbers of impulses from the key 66 over the line wires J, with the current flowing first in one direction and then in the opposite direction and an additional impulse each time with the current flowing in the first named direction, the selector is capable of responding to a number of different combinations and of selectively closing a number of different circuit controls. It should be understood that when impulses are sent over the line wires J from the key 66 that all selectors along the line are operated but that only the one having its arms 64 and 65 properly adjusted to correspond to the impulse combination being sent over the line from key 66 will be capable of closing a circuit control.

To those skilled in the art of railway signaling it is generally known that, when the "normal clear" system of signaling is used, an unoccupied insulated track section is normally energized and where light signals are used, a green lamp is lighted. Consequently by referring to the accompanying drawing a circuit for the track relay F may be traced as follows: from one side of the secondary 90 of the transformer K wire 89, one rail 86 of the track section E, wire 92, relay coil 103 of the track relay F, wire 91, the other rail 85 of the track section E and wire 88 back to the other side of the secondary 90 of the transformer K. Thus it can be seen that with no train on the track section E, the track relay F will be energized and consequently the armature 93 of the track relay F will be picked up and a circuit will be established as follows and will hereinafter for convenience be called circuit number one: from one side of the secondary 104 of the transformer L wires 105 and 106, lamp g 105 of the light signal G, wire 107, contact point 94, armature 93 of the track relay F in its energized position, wire 108, binding post 110, contact spring 26, contact point 109 of the answer-back mechanism A, and wire 111 110 back to the other side of the secondary 104 of the transformer L. From the circuit just traced it will be seen that with no train on the track section E and the track relay F picked up the lamp g which in this case is green will be lighted denoting to the operator of an approaching train that the section is "clear."

Should a train enter the track section E it will short circuit the track relay F in a manner also well known to those skilled in the art of railway signaling and the armature 93 of the relay F will drop, breaking contact with contact point 94, and consequently opening circuit number one which lighted the green lamp and will make contact with contact point 95 and will thereby establish a circuit herein called circuit number two, which may be traced as follows: from one side of the secondary 104 of the transformer L, wires 130

- 105 and 112, lamp *r* of the light signal G in wire 113 contact point 95 and then as in circuit number one for lighting the green light, through armature 93 of the track relay F in its deenergized position, wire 108, binding post 110, contact spring 26, contact point 109 of the answer-back mechanism A and wire 111 back to the other side of the secondary 104 of the transformer L. From the circuit just traced it will be seen that, when a train enters the track section E, the relay F is deenergized thereby causing the green light to be extinguished and the lamp *r* which in this case is red to be lighted 15 noting to the operator of an approaching train that the section is occupied.

From the foregoing description of circuits for the light signal G it will be seen that the said light signal G is capable of giving different distinctive indications said indications being controlled automatically by the track relay F which in turn is automatically controlled from the track section E. The object of this invention is to make possible the giving of an additional indication by the light signal G without in any way changing the construction of the light signal G or the circuits for the previously stated indications or their controls.

30 While the signal G shown is of the type capable of giving only two indications, obviously, other well known types of signals, including those capable of giving three different aspects, may be employed.

35 The train despatcher at the central station C being at all times familiar with the movements of all trains on his particular division may wish to get into telephonic communication with one of said trains to 40 give orders to the operator of said train or he may wish to have a particular train take a siding to permit a following train to pass at a certain point or for any other reason he may wish to give to the operator

45 of a train a signal that will be distinctive from all other signals said operator may encounter. Such a condition as just outlined being possible in the invention herein embodied, for instance a despatcher

50 may wish to get in touch with a train approaching the signal G which governs the track section E, therefore he causes the selector B to be operated by sending over the line wires J from the key 66 a combination

55 of impulses which will cause the H1 contacts on the selector B to be closed as above described and by so closing the said H1 contacts there is established a circuit number three from one side of the battery 134, wires

60 135, 136, 137, 138, 139, 140 and 141, the H1 contact fingers 142 and 143, of the selector B, in their closed condition, wires 144 and 145, coil 146 of the stick relay H, wires 147, 148 and 149 to the other side of the battery

65 134. From the last traced circuit it will be

seen by referring to the accompanying drawing that the coil 146 of the stick relay H has been energized and its armatures 96, 97 and 98 will be picked up and there will be established a circuit number four from 70 one side of battery 134, wires 135 and 150, the right-hand side of divided armature 80 of the stop relay D in the position shown in the drawing, its upstanding contact arm 81, contact point 83, wires 151 and 152, 75 armature 96 of the stick relay H in its upper position, contact point 99, wires 153 and 145, coil 146 of the stick relay H, wires 147, 148 and 149 back to the other side of battery 134. From the foregoing circuit it 80 can be seen that after the coil 146 is energized by the closing of circuit number three and the armature 96 has been picked up that the coil 146 will be held in its energized condition by the said circuit number four, after 85 the circuit number three, for energizing stick relay H, which is only momentarily closed, is broken. Another circuit is also formed when coil 146 of the stick relay H is energized which is a branch of circuit number 90 four, for holding stick relay H energized, and will hold coil 146 of the stick relay H in an energized condition after the breaking of the said circuit number four by the shifting of the stop relay D from the position 95 shown in full lines on the drawing to the position shown in dotted lines, as will be hereinafter more fully explained. This circuit may be traced as follows and is herein called circuit number five: from one side of 100 the battery 134, wires 135, 136, 137 and 154, contact post 20, contact finger 22, contact arm 6 in the position shown in the drawing and binding post 8 of the answer-back mechanism A, wires 155 and 152 armature 105 96, of the stick relay H, in the upper position, contact point 99, wires 153 and 145, coil 146 of stick relay H, wires 147, 148 and 149 back to the other side of the battery 134. When the coil 146 of the stick relay H is 110 energized by the forming of circuit number three, the armature 97 of the stick relay H is raised and makes contact with contact point 100 and a circuit which may be traced as follows is established and is herein called circuit 115 number six: from one side of battery 134, wires 135, 136 and 156, binding post 157, contact spring 24, contact point 158, wire 159, left-hand coil 11 of the answer-back mechanism A wires 160 and 161, front contact 120 point 100 and armature 97, of the stick relay H, in its upper position, wires 162, 148 and 149 back to the other side of battery 134. The above traced circuit number six by energizing the coil 11 of the answer-back 125 mechanism A, causes armature 15 to be attracted by core 13 and the arm 16 fixed to the armature 15 to be rocked to the right and pawl 18, carried by the arm 16, to engage the teeth 4 on the answer-wheel 1 and 130

to rotate said answer-wheel 1, one step in a clockwise direction. Current flowing as traced in circuit number six sets up a magnetic flux in the core 13 and the oscillatable control armature 23 is attracted by the core 13, as fully set forth in the above mentioned prior application Serial #16,863, and rotated about its axis in the direction indicated by the arrow *a*. As the control armature 23 is rotated about its axis, the downwardly extending arm 23¹ moves with it in the direction indicated by the arrow *a* and the block 23² strikes the contact spring 24 forcing it out of contact with the contact point 158 and thereby momentarily breaking circuit number six for energizing coil 11 on the answer-back mechanism or in other words the armature 23 breaks its own operating circuit. As soon as circuit number six is broken and the armatures 15 and 23 are released they return to their neutral positions, the armature 23 by its own weight and the armature 15 as actually constructed and explained in my prior application herein above referred to being provided with a centering device. Thus the circuit number six is again completed by the contact spring 24 again coming in contact with contact point 158, to again energize the coil 11 and thus said coil 11 may be automatically energized and deenergized under the influence of the said circuit number six and the armatures 15 and 23 to assure automatic continuous step by step rotation of the answer-wheel 1 until it is stopped as hereinafter explained.

The answer-wheel 1 as before described has long and short teeth formed in its outer periphery, the long teeth being arranged in code groups and being adapted to engage the roller 30 on the arm 29 and by means of circuits formed by the lifting of arm 29, to send impulses corresponding to the code groups over the telephone line wires *J* to the telephone receiver 75 at the central station *C*. These code groups may be arranged in any desired series and any desired number of groups but in this particular case the answer-wheel 1 has three code groups which are arranged in series of 3-2 combinations, each series comprising three long teeth spaced the distance of one short tooth from two other long teeth. Each series of five teeth being arranged about the outer periphery of the answer-wheel 1 in such a manner that radial lines drawn through the center of each group will be one hundred and twenty degrees apart, which also is the space between the arm carried rollers 9 adapted to coat with the notch 10 in the inner periphery of the answer-wheel 1. As explained more fully hereinafter, the answer-wheel 1 is automatically stopped in one position when the roller 9 on the arm 5 is in the notch 10, as shown on the drawing, and in

the other position when the roller 9 on the arm 6 is in said notch 10; and since the answer-wheel 1 in moving from either one of these positions should, in order that the correct indication may be given, commence one of the code sequences or series of five teeth, it is necessary to space the rollers 9 on the arms 5 and 6 apart for an arc of one hundred and twenty degrees, that is, the same arc as is included in the sector wherein are located each series of five long teeth.

At the same time that block 23² strikes the contact spring 24, the block 23², which is also located on the arm 23¹, strikes the contact spring 26 and in a like manner forces contact spring 26 away from its contact point 109 and interrupts circuit number one, for lighting the green light in signal *G* but as before described, the circuit number six which controls armature 23 and arm 23¹ being at the same time broken the arm 23¹ will return to its middle position and circuit number one will be again closed. As also described with reference to circuit number six, the said circuit number six will be intermittently made and broken and it will therefore be obviously apparent that the same condition will be true in the case of circuit number one and also when the track section *E* is occupied and circuit number two is effective a similar condition will exist. From the foregoing description it will readily be seen that if either the green lamp *g* or the red lamp *r* in signal *G* is lighted that its circuit will be intermittently made and broken and the light will be intermittently flashed and will so continue until the answer-back mechanism *A* is stopped as hereinafter explained.

When the answer-wheel 1 is rotated continuously in a clockwise direction as before described, the roller 30 coats with the long teeth on the answer-wheel 1 and arm 29 is lifted to establish two separate electrical circuits and to give repeated distinctive 3-2 110 clicks audible in the telephone located at the central station or despatcher's office *C*. The first of said circuits may be traced as follows and is herein termed circuit number seven: from one side of battery 134, wires 135, 136, 137, 138 and 163, the primary 46¹ of an induction coil 46, wires 164, binding post 38, contact finger 36, its contact 34, contact 32 on member 29, member 29, its other contact 31, contact 33 on contact finger 35, 120 contact finger 35, binding post 37 and wire 165 back to such portion of the battery 134 as shall assure passage of only so much of its energy as may be necessary for completing the answer-back circuits and making the 125 answer-back clicks sufficiently audible at the telephone which is included in a circuit number eight induced by making and breaking circuit number seven and may be traced as follows: from one side of the secondary 130

46² of the induction coil 46, wire 164, binding post 38, contact finger 36, its contact 34, contact 32 on member 29, member 29, arm 27, binding post 28, wires 166, 126 and 125, line 5 wire 124 of the telephone line wires J, wires 119 and 167, telephone receiver 75 at the central station C, wires 168 and 118, line wire 132 of the telephone line wires J, wires 131, 130 and 169, binding post 45, contact finger 10 44, its contact 43, contact 42 on contact finger 40, contact finger 40, binding post 41 and wire 170, condenser 171 and wire 172 back to the other side of secondary 46² of the induction coil 46.

15 From the above traced circuits numbered seven and eight it will be apparent that the 3-2 clicks will continue to be heard in the telephone receiver 75 as long as the answer-wheel 1 rotates in a clockwise direction and 20 the despatcher will be informed that the stick relay H has been picked up, and that the answer-wheel 1 is being operated in a clockwise direction and also after three such code groups have been received and the answer-back 25 still continues to come in the despatcher is assured that the operations are continuous, for reasons hereinafter more fully explained, and that the signal light is being flashed continuously. To stop the rotation 30 of the answer-wheel 1 and the consequent audible indications, the despatcher by operating the key 66, causes the necessary impulses to be sent over the line wires for operating the selector B to close the ST contacts, thereby establishing a circuit herein 35 called circuit number nine and may be traced as follows: from one side of battery 134, wires 135, 136, 137, 138, 139, 140 and 173 ST contact fingers 174 and 175, wire 176, coil 40 76 of the stop relay D, wires 177, 178, 179 and 149 back to the other side of battery 134. From circuit number nine just traced 45 it will be seen that coil 76 becomes energized and the lefthand side of armature 80 of the stop relay D is attracted by the core 78 and moves contact arm 82 on armature 80 into the position shown in dotted lines on the drawing and into contact with contact point 84, at the same time bringing contact 50 arm 81 out of contact with contact point 83 and interrupting circuit number four which is one of the two circuits which hold the stick relay H in its energized or stuck up condition, however the stick relay H will 55 remain in its energized or stuck up condition due to circuit number five and the answer-wheel 1 will continue to rotate in the clockwise direction until the notch 10 comes opposite the roller 9, on the arm 6, when said 60 roller 9 will drop into said notch 10, on the inner periphery of the answer-wheel 1, interrupting circuit number five, for sticking up stick relay H and causing the armatures 96 and 97 and 98 of the said stick relay H to drop, thereby interrupting circuit number 65

six for energizing coil 11 and stopping the continuous rotation of the answer-wheel 1.

When the coil 146 of the stick relay H is deenergized by the interrupting of its stick circuit herein numbered five and the armatures 97 and 98 drop there is established a circuit for the answer-back coil 11 and a circuit for the answer-back coil 12 and are herein numbered ten and eleven respectively.

Circuit number ten may be traced as follows: commencing at one side of battery 134, wires 135, 136, 137 and 154, contact post 20, contact finger 21, contact arm 5 with its roller 9 out of notch 10, binding post 7, wire 180, contact spring 25, contact point 181, 75 wires 182 and 183, coil 12 of the answer-back mechanism A, wire 184, back contact point 101 and armature 97 of the stick relay H in its deenergized condition, wires 162, 148 and 149 back to the other side of battery 134. 80

Circuit number eleven may be traced as follows: commencing at one side of battery 134, wires 135, 136 and 156, binding post 157, contact spring 24, contact point 158, wire 159, coil 11 of the answer-back mechanism 90 A, wires 160 and 185, back contact point 102 and armature 98 of the stick relay H in its deenergized condition, wire 186, contact point 84, contact arm 82 and the lefthand end of armature 80 of the stop relay D in the 95 position shown in dotted lines on the drawing, wires 187, 178, 179 and 149 back to the other side of battery 134.

The dropping of the armatures 97 and 98 close a break in each of circuits numbers ten and eleven and at the instant that the said armatures 97 and 98 reach their lower position and make contact with contact points 101 and 102 respectively, the control armature 23 is still oscillating and may at that 100 instant be in position to close either or perhaps both of these circuits at the contact springs 24 and 25. Assuming that the control armature 23 has been moved in a direction opposite to that indicated by the arrow 105^a and that the contact spring 25 is separated from its contact point 158 at the time the armatures 97 and 98, of the stick relay H, drop, then the circuit first made will be through contact spring 24 and contact point 110 158 which are closed at that time as in circuit number eleven for coil number 11. The answer-wheel 1 will thus be rotated one step in a clockwise direction; the control armature 23 will move in the direction indicated 115 by arrow ^a and arm 23¹ will cause contact springs 24 and 26 to be separated from their respective contact points 158 and 109, in a manner before described, to interrupt their 120 respective circuits. As soon as the circuit number eleven for the coil 11 has been interrupted, the circuit number ten for coil number 12 causes the armature 15 to be attracted and the answer-wheel to rotate one 125 step in a counterclockwise direction as here- 130

inbefore described. It therefore can be seen that circuits numbers ten and eleven will alternately be made and broken and the coils 11 and 12 on the answer-back mechanism A will be alternately energized and deenergized causing the answer-wheel 1 to be stepped first one step in one direction and then one step in the opposite direction, or in other words the roller 9 on the arm 6 will ride out of and into the notch 10 on the answer-wheel 1, said answer-wheel 1 continuing to be so operated until stopped by the despatcher which will be hereinafter more fully explained. If instead of circuit number eleven for coil 11, circuit number ten for coil 12, had been made the result would have been the same after the first making and consequent breaking of the circuit ten had been accomplished and the answer-wheel 1 would have operated in the manner just described. If it should happen that the control armature 23 is in the middle position at the instant armatures 97 and 98 drop, the same operation of the answer-wheel 1 will occur, since one or the other of the coils 11 or 12 would preponderate in its attraction of armature 15.

By referring to the drawing it will be seen that as the coils 11 and 12 on the answer-back mechanism A are alternatively energized and deenergized that the control armature 23 will be alternatively attracted by cores 13 and 14 and that the arm 23¹ on control armature 23 will alternately open and close the circuits through contact springs 24 and 25. It will also be seen that contact spring 26, which is included in both circuits numbers one and two for the green and red lamps respectively of the signal G, will be broken each time the arm 23¹ swings to the right or in a direction indicated by the arrow a and that the lamp in the signal G which is lighted at that time, depending upon whether or not the track section E is occupied, will be continuously flashed, thereby giving a third indication which is distinctive in character, to the operator of a train.

When the operator of a train has recognized the flashing signal and has reported to the despatcher that his order has been carried out, the despatcher at the central station C may stop the flashing and does so by operating the selector and the key 66 as before described and causing the group of CL contacts to be closed, thereby establishing a circuit which is herein called circuit number twelve and may be traced as follows: commencing at one side of battery 134, wires 135, 136, 137, 138, 139 and 188 C, L, contacts 189 and 193 of the selector B wires 194 and 183, coil 12 on the answer-back mechanism A, wire 184, back contact point 101 and armature 97 of the stick relay H in the deenergized condition, wires 162, 148 and 149 back to the other side of battery 134. From the circuit just traced it will be noted that the coil 12 is energized and that the answer-wheel 1, in a manner fully described, will be rotated one step in a counterclockwise direction. The roller 9 on the arm 5 will therefore be moved out of the notch 10 on the answer-wheel 1 and contact finger 21 will make contact with contact 130

referring to the drawing that coil 77 on the stop relay D is energized and the armature 80 and also its contact arms 81 and 82 will be moved from the position last occupied or the position shown in dotted lines 70 on the drawing to the position as shown in full lines on the drawings, thereby interrupting circuit number eleven for coil 11, of the answer-back mechanism A, however circuit number ten for coil 12 being made 75 through contact finger 21 and contact post 20 of the answer-back mechanism A will now rotate the answer-wheel 1, step by step in a counterclockwise direction until the notch 10, on the answer-wheel 1, comes 80 opposite the roller 9 when said roller 9 will drop into said notch 10 and interrupt the circuit number ten for the coil 12 thus stopping the rotation of the answer-wheel 1. After circuit number eleven for coil 11 85 is interrupted and the answer-wheel 1 is rotated in a counterclockwise direction by the action of circuit number ten for coil 12, two series of 2-3 answer back clicks will be sent over the line, in a manner before described, to the telephone in the central station C informing the despatcher that the devices have operated correctly and that the flashing of the lamp in the signal G has stopped. It will be noted that in this case 95 the answer-back indication while it is composed of the same series of clicks or impulses, they are sent over the line in the reverse order, namely, 2-3 instead of 3-2 as was the order of the first indication received by 100 the despatcher and herein before described. This condition of the indication will inform the despatcher that the answer-wheel is operating in a counterclockwise direction and that the stick relay H is in the deenergized condition and also that the stop relay D is in its righthand position.

Should the same or a succeeding despatcher wish at any time to verify the condition of the signal as to whether a lamp is 110 flashing or is lighted steadily, he may cause the CL contacts to be closed in a manner fully explained above thereby establishing a circuit number thirteen, which may be traced as follows: from one side of the 115 battery 134, wires 135, 136, 137, 138, 139 and 188 C, L, contacts 189 and 193 of the selector B wires 194 and 183, coil 12 on the answer-back mechanism A, wire 184, back contact point 101 and armature 97 of the 120 stick relay H in the deenergized condition, wires 162, 148 and 149 back to the other side of battery 134. From the circuit just traced it will be noted that the coil 12 is energized 125 and that the answer-wheel 1, in a manner fully described, will be rotated one step in a counterclockwise direction. The roller 9 on the arm 5 will therefore be moved out of the notch 10 on the answer-wheel 1 and contact finger 21 will make contact with contact 130

post 20 thereby reestablishing circuit number ten. This circuit will then cause the answer-wheel 1 to make one complete revolution in a counterclockwise direction and 5 will automatically stop when the notch 10 of the answer-wheel 1 comes opposite the roller 9 on the arm 5. During the rotation of the answer wheel 1 as just described it will obviously be seen that three series of 10 answer back 2-3 indications will be sent over the line and will be audible in the despatcher's telephone. This will assure him that the stick relay is in its deenergized condition and that the stop relay D is in its 15 right-hand position, the position shown in the drawing, and consequently that the signal lamp is not flashing.

On the other hand if a despatcher after having set a signal flashing and having 20 stopped his answer-back indications as before described, wishes to check himself or the signal he may again cause the HI contacts to be closed in a manner fully described. This will reestablish circuit number 25 three for energizing the stick relay H, thus interrupting both circuits number ten and eleven for coils 12 and 11 respectively. However when the armature 97 on relay H is lifted, it again makes contact with contact point 100 and circuit number six for coil 11 is again established. As the system is herein shown, the despatcher should be careful in the above case to hold the key 66 closed a moment after sending the necessary 30 impulse in order that the HI contact fingers 142 and 143 will remain closed long enough for the circuit number six to step the answer-wheel 1, one step in a clockwise direction and thus assure the reestablishing 35 of circuit number five, which is closed when the roller 9 on the arm 6 is out of the notch 10 and the contact finger 22 bears against contact post 20. Said circuit number five will then hold the stick relay H energized 40 until the answer-wheel 1 makes a complete revolution in a clockwise direction and the notch 10 again comes opposite the roller 9 on the arm 6 causing said roller to drop into said notch and to break circuit number 45 five for sticking up said relay H. It will be noted that since the answer-wheel 1 has made a complete revolution, three sets of 3-2 answer-back indications will have been sent over the line to the despatcher assuring 50 him that the signal was flashing at that time, for if the condition of the signal had been otherwise the answer-back indication received by him would have been continuous instead of only three sets. As soon as the 55 stick relay H becomes deenergized by the breaking of circuit number five, the armatures 97 and 98 of said relay H will drop and again make contact with contact points 101 and 102 thus reestablishing circuits 60 numbers ten and eleven for coils 12 and 11

respectively. From the foregoing description it will be seen that it is possible to make a check on the flashing of the lights in the signal G without interrupting said flashing.

In describing the construction and operation of this invention, reference has been made to the apparatus at only one station along the track; but it should be clearly understood that in practice a number of 70 similarly equipped stations along the track would be used, the apparatus at all of these stations being connected to the same line circuit. The apparatus embodying the invention would not ordinarily be applied to every 75 block signal of the block signaling system, but only to those block signals which were located adjacent to sidings or at other points where it is found desirable to give orders to the crews of passing trains. The apparatus embodying this invention used at each 80 of the several stations would be constructed the same, with the exception that the selectors at these stations would be adjusted so that their groups of contacts would be 85 operated by different and distinctive series of impulses, and the answer-wheels at the several stations would be provided with different groupings of long and short teeth so as to provide for the sending of different 90 and distinctive code signals.

It should be understood that there are other features of the answer-back mechanism that have not been brought out but as they are not involved in this invention 100 and are fully shown and described at length in my prior application hereinbefore referred to, it is not considered necessary in this case to discuss them further.

Although I have particularly shown and 105 described the construction of one physical embodiment of my invention, and explained the operation and principle thereof; nevertheless, I desire to have it understood that the form selected is merely illustrative, but 110 does not exhaust the possible physical embodiments of the idea of means underlying my invention.

What I claim as new and desire to secure by Letters Patent in the United States, is: 115
 1. In a signaling system, in combination: a way-side signal provided with an electric lamp; a local signal circuit including said lamp; electrically operable means for periodically opening and closing said circuit to cause flashing of the lamp; means controlled from a central station for governing the operation of said means; and answer-back means for giving at the central station a code signal indicating that said electrically operable means is operating.

2. In a signaling system, in combination: a way-side signal; a local signal circuit for governing said signal; electrically operable means for periodically opening and closing 120

said circuit to give said way-side signal an arrestive aspect; means controlled from a central station for determining the operation of said means; and answer-back mechanism for sending a code signal to the central station indicating that said last-mentioned means has been placed in condition to cause operation of said electrically operable means.

10 3. In a signaling system, in combination: a way-side light signal, a local signal circuit for governing said signal; electrically operable means for intermittently opening and closing said circuit; controlling devices 15 for said means; means controlled from a central station for placing said controlling devices into condition to cause operation of said means; and answer-back means for giving at the central station a code signal 20 indicating the operated condition of said controlling devices.

4. In a signaling system, in combination: an impulse transmitting device located at a central station; means located at a point 25 remote from said central station selectively controlled by said transmitting device; a relay momentarily controlled by said first mentioned means; means for controlling said relay after said first mentioned means has 30 become ineffective; means controlled by said relay for giving at said central station a persistent code indication of the operated condition of said relay; means selectively controlled by said first mentioned means for 35 causing said persistent indication to stop and for rendering said second mentioned means ineffective; a circuit; means controlled by said relay in its ineffective condition for intermittently opening and closing said circuit 40 for any desired length of time and means also selectively controlled by said first mentioned means for rendering said last mentioned means ineffective.

5. In a signaling system, in combination: 45 a way-side signal provided with lamps; a local signal circuit including said lamps; electrically operable means for opening and closing said circuit intermittently; controlling devices for said means; means controlled from a central station for governing said controlling devices; answer-back mechanism for sending a signal to the central station; and means including said answer-back mechanism for indicating the operated 55 condition of said controlling devices at any time without changing such operated conditions.

6. In a signaling system, in combination: a relay; means for energizing said relay 60 from a distant point; means for holding said relay in its energized condition after said first mentioned means has become ineffective; answer-back means controlled by said relay in its energized condition for giving

at said distant point persistent code indications of the energized condition of said relay; means for rendering said second mentioned means ineffective and for causing said persistent indications to stop; a signal; lamps for said signal; a circuit for said 70 lamps; means controlled by said relay for intermittently opening and closing said circuit to cause said lamps to be intermittently flashed for any desired length of time; means controlled by said first mentioned 75 means for causing said flashing to stop; other answer-back means controlled by said relay in its de-energized condition for giving at said distant point repeated code indications, distinctive in character from the first 80 mentioned indications, that said flashing has been stopped; and means controlled from said distant point for verifying said stopped condition.

7. In a signaling system, in combination: 85 an insulated stretch of railway track; a circuit for said stretch of railway track; a relay included in said circuit; a signal for said stretch of track controlled by said relay; lamps for said signal; a circuit for said 90 lamps; means controlled from a distant point for intermittently opening and closing said circuit for said lamps to cause said lamps to be flashed for any desired length of time; means at said distant point for verifying said flashing condition of said lamps and means controlled from said distant point for causing said flashing to stop.

8. In a signaling system, in combination: 100 a plurality of insulated track sections; a circuit for each of said track sections; a signal for each of said track sections, capable of assuming different operated conditions; a circuit for each of said signals, automatically controlled by said first mentioned 105 circuit; means for intermittently opening and closing said last mentioned circuit for any desired length of time; and means controlled from said central station for governing the operation of said mentioned means. 110

9. In a signaling system, in combination: 115 a relay; means selectively controlled from a central station for energizing said relay; means for holding said relay energized after said first mentioned means has become ineffective; answer-back means controlled by said relay for sending to said central station persistent code indications of the energized condition of said relay; other means selectively controlled from the central station for 120 rendering said holding means ineffective; and means for stopping said answer-back means at the end of a code.

10. In a signaling system, in combination: 125 a relay; means selectively controlled from a distant point for energizing said relay; means for holding said relay energized after said first mentioned means has become in-

effective; answer-back means controlled by said relay for sending to said distant point persistent indications of the energized condition of said relay; other means controlled from said distant point for rendering said second mentioned means ineffective; other means for holding said relay energized after said second mentioned means has been rendered ineffective and means governed by said answer-back means for automatically rendering said last mentioned means ineffective and for stopping said persistent code indications.

11. In a signaling system, in combination: a relay; means selectively controlled from a central station for momentarily energizing said relay; a stick circuit for said relay; means selectively controlled from the central station for interrupting said stick circuit; answer-back mechanism controlled by said relay for sending code indications to said central station; a second stick circuit for said relay; and means governed by said answer-back mechanism for automatically interrupting said second stick circuit at the end of a code.

12. In a signaling system, in combination: a railway track divided into blocks; a signal associated with a block; circuits governed in accordance with traffic conditions for controlling the indications of said signals; means controlled from a central station for periodically opening and closing a common branch of said circuits; and answer-back mechanism for sending to said central station a signal telling of the operation of said means.

13. In a signaling system, in combination: a railway track provided with a plurality of track circuited sections; a signal associated with each of said sections; circuits for each of said signals governed in accordance with traffic conditions; means controlled from a central station for periodically opening and closing a common branch of said circuits; and answer-back mechanism for sending to said central station code indications indicating the operation of said means which are distinctive for each of said signals.

14. In a signaling system, in combination: a railway track provided with a plurality of blocks; a signal associated with each of said blocks, said signal being capable of assuming different indicating conditions; a circuit for each of said signals governed in accordance with traffic conditions; and means selectively controlled from a central station for causing any one or more of said signals to assume an additional indicating condition distinctive from its other indicating conditions.

15. In a signaling system, in combination: a track provided with a plurality of blocks; a signal associated with each of said blocks,

said signal being capable of assuming different indicating conditions; circuits for each of said signals governed in accordance with traffic conditions; means selectively controlled from a central station for causing any one or more of said signals to assume an additional indicating condition distinctive from its other indicating conditions; and answer-back mechanism for sending to said central station a code signal indicating that said means is operating, said codes being different for each of said signals.

16. In a signaling system, the combination with an automatic block signal, capable of giving different indications to a passing train, of a central station, means for automatically governing the indication of said signal in accordance with traffic conditions, and means controlled from said central station for causing said signal to give an additional indication to said passing train which is distinctive from each of the other automatically controlled indications.

17. In a signaling system, the combination with an automatic block signal, capable of giving different indications to a passing train, of a central station, means for automatically governing the indications of said signal in accordance with traffic conditions, means controlled from said central station for causing said signal to give an additional indication to said passing train which is distinctive from its other automatically controlled indications, and answer-back means for giving at said central station a code signal indicating that said last mentioned means is operating.

18. In a signaling system, the combination with an automatic block signal, capable of giving different indications to a passing train, of a central station, means for automatically governing the indications of said signal in accordance with traffic conditions, automatic apparatus controlled from said central station for causing said signal to give an additional indication to said passing train which is distinctive from its other automatically controlled indications, answer-back means for giving at said central station a code indication of the operating condition of said apparatus, and means controlled from said central station for enabling a repetition of said code indication of said operating condition to be obtained any number of times without changing such existing operating condition.

19. In a signaling system, the combination with a plurality of block signals, each capable of giving different indications to a passing train, of a central station, means associated with each of said signals for automatically governing its indications in accordance with traffic conditions, and means associated with each signal and selectively

controlled from said central station for causing any one or more of said signals to give an additional indication to said passing train which is distinctive from its other automatically controlled indications.

20. In a signaling system, the combination with a plurality of automatic block signals, each capable of giving different indications to a passing train, of a central station, means associated with each of said signals for automatically governing its indications in accordance with traffic conditions, automatic apparatus associated with each signal and selectively controlled from said central station for causing any one or more of said signals to give an additional indication to said passing train which is distinctive from its other automatically controlled indications, and answer back means associated with each of said signals for sending to said central station a code indication of the operating condition of said apparatus, said code indications being distinctive for the different block signals.

21. In a signaling system, the combination 25 with a plurality of automatic block signals, each capable of giving different indications to a passing train, of a central station, means associated with each of said signals for automatically governing its indications in accordance with traffic conditions, automatic 30 apparatus associated with each signal and selectively controlled from said central station for causing said signal to give an additional indication to said passing train 35 which is distinctive from its other automatically controlled indications; and means controlled from said central station for enabling a distinctive code indication to be obtained at the central station from any one of the 40 block signals telling of the operating condition of the corresponding apparatus, this means permitting such code indication to be obtained any number of different times without changing the existing operating 45 condition of the corresponding apparatus.

RICHARD C. LEAKE.
